(57) **CLAIM**

The ornamental design for an accessory for vehicle heating and air conditioning systems, as shown and described.

DESCRIPTION

FIG. 1 is a perspective front view of an accessory for vehicle heating and air conditioning systems showing our new design;

FIG. 2 is a top plan view of the accessory for vehicle heating and air conditioning systems of FIG. 1;

FIG. 3 is a front elevation view of the accessory for vehicle heating and air conditioning systems of FIG. 1;

FIG. 4 is a right side elevation view of the accessory for vehicle heating and air conditioning systems of FIG. 1;

FIG. 5 is a left side elevation view of the accessory for vehicle heating and air conditioning systems of FIG. 1;

FIG. 6 is a bottom plan view of the accessory for vehicle heating and air conditioning systems of FIG. 1;

FIG. 7 is a rear elevation view showing the vanes flat with the back of the accessory for vehicle heating and air conditioning systems of FIG. 1;

FIG. 8 is a perspective front view of an accessory for vehicle heating and air conditioning systems showing our another alternate design of the embodiment shown in FIG. 1;

FIG. 9 is a top plan view of the accessory for vehicle heating and air conditioning systems of FIG. 8;

FIG. 10 is a front elevation view of the accessory for vehicle heating and air conditioning systems of FIG. 8;

FIG. 11 is a right side elevation view of the accessory for vehicle heating and air conditioning systems of FIG. 8;

FIG. 12 is a left side elevation view of the accessory for vehicle heating and air conditioning systems of FIG. 9;

FIG. 13 is a bottom plan view of the accessory for vehicle heating and air conditioning systems of FIG. 9; and,

FIG. 14 is a rear elevation view showing the vanes flat with the back of the accessory for vehicle heating and air conditioning systems of FIG. 9.

(Continued)

In the drawings, the broken lines depict unclaimed subject matter only and form no part of the claimed design.
